UNITED STATES PATENT OFFICE.

OTTO STROBERGER AND REZIE E. LEE, OF CREIGHTON, NEBRASKA.

ENGINE-CYLINDER DRESSER.

1,389,850.

Specification of Letters Patent. Patented Sept. 6, 1921.

Application filed November 1, 1920. Serial No. 421,016.

To all whom it may concern:

Be it known that we, OTTO STROBERGER and REZIE E. LEE, citizens of the United States, and residents of Creighton, in the 5 county of Knox and State of Nebraska, have invented a new and useful Improvement in Engine-Cylinder Dressers, of which the following is a specification.

Our invention relates to engine cylinder 10 dressers or finishers and has as its all important object the provision of a device which may be readily inserted in the engine cylinder and effectively lap or finish the interior thereof.

15 Further, the invention provides a rotatable cylinder lapper or finisher which includes a pair of complementary semi-cylindrical sections provided with means for holding an abrasive sheet thereon which will 20 be held firmly at all times against the inner walls of the cylinder during the rotation of the device.

The invention also provides a rotatable abrasive holder including a pair of semi-cylindrical sections resiliently moved away 25 from each other to hold the abrasive material in working position against the inner face of the cylinder.

The invention also provides a device of 30 this character which may be used in conjunction with any conventional type of rotating tool holder.

With the preceding and other objects and advantages in mind that will become apparent from the following disclosure, the invention consists in the novel combination of elements, and arrangements of parts and operations to be hereinafter specifically referred to, claimed and illustrated in the accompanying drawings, wherein:

Figure 1 is a side elevation of the device in operation, parts of the engine being operated on, being shown in cross section.

Fig. 2 is an end elevation of the device.

45 Fig. 3 is an enlarged side elevation of the device detached from the rotating tool holder.

Fig. 4 is a sectional view taken on line 4-4 of Fig. 2.

50 Fig. 5 is a perspective of one of the elements embodied in the combination.

Referring in detail to the drawings, wherein similar characters of reference designate corresponding parts throughout the several 55 views, the numeral 5 designates a conventional type of lathe or other metal working

machine and includes a rotatable chuck or tool holder 6.

Our improved cylinder dresser or lapper, as reduced to practice, consists of a pair 60 of complementary semi-cylindrical abrasive holders or sections 6 upon the inner face of each of which is a boss 7 provided with a recess 8. A pin 9 extends transversely from one section to the other and has its ends engaged in the recesses 8. The ends of this pin 9 stop short of the end walls of the recesses 8 so that the sections 6 may be moved laterally toward each other. The numeral 10 designates a shank having one end secured in 70 the rotating chuck or tool holder 6 and has its opposite end formed with an eye 11, which is disposed on the pin 9. Centrally of its end and held in this position by a set screw 12, encircling the pin 9 and located 75 upon opposite sides of the eye 11 are coil springs 13, the inner end of each of which bears against this eye 11 while its opposite ends bear against the adjacent boss 7 and thereby urges the sections 6 away from each 80 other.

As shown in Figs. 2 and 3, the sections 6 are formed with, upon their outer faces and at their longitudinal edges, longitudinal recesses 14. Disposed upon the outer face of 85 each of the sections 6 is a sheet of emery cloth or other abrasive material 15. One end of each of these sheets is disposed in one of the recesses 14 and is held therein by clamping bars 16, the latter being detachably held 90 in the recess 14 by fastenings 17. The opposite ends of each of these sheets 15 is held in the other recess of their respective sections by a resilient clamping bar 18 having its ends formed with clips 19 engaging the 95 notches 20 located at the ends of the section 6.

In order to limit the outward movement of the sections 6, when the same are not engaged within the cylinder, there is provided 100 a pair of longitudinally curved plates 21 which are secured to the inner face of the sections at their longitudinal edges by fastenings 22. One end of these plates is provided with a longitudinal slot 23 through 105 which pins or screws 24, carried by the section 6, extend.

In operation, the sections 6 are moved toward each other to permit the same to be received in the cylinder of the engine. Inasmuch as these sections 6 are under the influence of the springs 9, they are urged away

from each other and resiliently hold the abrasive sheets against the inner face of the cylinder.

It is to be understood that the form of our invention herein shown and described is to be taken as a preferred example of the same, and that various changes in the shape, size and arrangement of parts may be resorted to without departing from the spirit of the invention or the scope of the subjoined claim.

Having thus described our invention, what we claim as new and desire to secure and protect by Letters Patent of the United States, is:

A device of the character described, comprising a pair of complementary semi-cylindrical sections each of which being provided with a recess in its inner face and located at diametrically opposite points, said sections being also provided with longitudinal recesses upon their outer faces and at their

longitudinal edges, abrasive sheets embracing the outer faces of the sections and having their ends disposed in the recesses, clamping bars holding one end of each sheet 25 in position, and resilient clips disposed in the other recesses and holding the opposite ends of the sheets in place, a pin having its ends engaged in the recesses, a shank adapted to be connected with a rotating tool and provided with an eye at one end through which the pin extends and has positive connection therewith, coil springs on the pin bearing against the eye and sections to urge the latter away from each other, plates 30 carried by the inner face of each section, each of which being provided with a slot, and a pin carried by each section and engaged in the slot.

OTTO STROBERGER.
REZIE E. LEE.
